UNITED STATES PATENT OFFICE.

M. V. OLRY, OF PHILADELPHIA, PENNSYLVANIA.

IMPROVED CAP FOR BOTTLES.

Specification forming part of Letters Patent No. 58,281, dated September 25, 1866.

To all whom it may concern:

Be it known that I, M. V. OLRY, of Philadelphia, Pennsylvania, have invented a Neck-Cap for Bottles; and I do hereby declare the following to be a full, clear, and exact description of the same, reference being had to the accompanying drawings, and to the letters of reference marked thereon.

My invention consists of two metal tubes connected together at the top, the whole being constructed for attachment to the necks of bottles, and so as to form a neat and secure cap for the same, as fully described herein-after.

In order to enable others to make my invention, I will now proceed to describe the manner of constructing and applying the same.

On reference to the accompanying drawings, which form a part of this specification, Figure 1 is a sectional view of my improved neck-cap for bottles, &c.; Fig. 2, the same applied to a bottle; Fig. 3, a sectional plan on the line 1 2, Fig. 2; Fig. 4, a modified form of band; and Fig. 5, the same applied to a bottle.

The neck-cap consists of a band or tube, A, of metal, and a somewhat thinner tube, b, the two tubes being connected together at the top by the annular piece a, and the whole, if desired, being made in one piece. When this cap has to be secured to a bottle, X, the neck of the latter is coated with any suitable cement, x, the band is fitted in its place, and the lower end of the tube b is expanded by any suitable instrument, so as to bear against the enlarged portion of the inside of the neck, as shown in Fig. 2, when the band will be securely confined in its position.

In many instances the lower end of the tube b may be expanded to such an extent that the neck-cap can be held in its place without the use of cement.

Neck-caps of the ordinary construction are generally secured in their places by cement alone, and are so formed that the contents of the bottle frequently come in contact with the cement, and so soften the latter that the cap becomes loose.

It will be seen that when a cap of the above description is used the cement may, if desired, be dispensed with, and that, should it be used, the contents of the bottle cannot under any circumstances reach it.

It will also be seen that it is not necessary to use especial care in forming the neck of the bottle to receive the cap, that the latter may be readily and cheaply made, and that the improved cap gives a neat finish to the neck of the bottle.

The neck may have external screw-threads for receiving a screw-cover, B, similar to that of an ordinary flask, as seen in Figs. 1 and 2; or the neck-cap may be plain, as seen in Figs. 4 and 5, for the reception of a stopper, D.

It will be evident that the neck-cap is susceptible of being highly ornamented, and that it may be modified in form without departing from the main features of the invention.

I claim as my invention, and desire to secure by Letters Patent—

The within-described neck-cap for bottles, the same consisting of the two tubes A and b, connected together at the top and constructed for attachment to the neck of a bottle, substantially in the manner described.

In testimony whereof I have signed my name to this specification in the presence of two subscribing witnesses.

M. V. OLRY.
